Atty's.

UNITED STATES PATENT OFFICE.

WILLIAM B. WATERS, OF ATLANTIC CITY, NEW JERSEY.

HEATER FOR FIRE-ENGINES.

SPECIFICATION forming part of Letters Patent No. 783,601, dated February 28, 1905.

Application filed November 8, 1904. Serial No. 231,930.

To all whom it may concern:

Be it known that I, WILLIAM B. WATERS, a citizen of the United States, residing at Atlantic City, New Jersey, have invented certain new and useful Improvements in Heaters for Fire-Engines, of which the following is a specification.

My invention relates to heaters for steam fire-engines, and particularly to a valve device which when the fire-engine leaves the engine-house will be automatically operated to cut off the flow of fuel to the burner which is utilized for heating the water of the boiler of the engine during the time that the said engine is at rest in the engine-house.

The invention consists in the features and combination and arrangement of parts hereinafter described, and particularly pointed out in the claim.

20 In the accompanying drawings, Figure 1 is a side view of a part of the steam fire-engine with my improvement attached. Fig. 2 is a sectional view of the automatic cut-off valve for the fuel-supply.

25 My invention belongs to that class of apparatus which is designed to heat the water of a fire-engine boiler while the engine is at rest within the engine-house, so that in case of fire the engine on leaving the engine-house 30 will have its boiler containing hot water ready to make steam as soon as the fire is started in the furnace.

In the drawings, 1 represents the boiler of the fire-engine; 2, one of the carrying-wheels. 35 Pipes 3 connect with the boiler and with a heating-coil 4, arranged within a casing 5, supported in any suitable manner within the engine-house, to be fixed therein and to be disconnected from the engine when the same 40 starts for the fire. The detachable connections lie in the pipes 3 and consist of slip-joints 6 of any well-known form provided with check-valves adapted to automatically close when the two parts of the pipes 3 are disconnected.

45 Beneath the coil 4 is arranged a burner adapted to burn gas or other fuel, this burner being a fixture within the engine-house. The supply-pipe to the burner is indicated at 7, and in this pipe a coupling 8 is arranged containing ports 9, through which the fuel passes

from the pipe 7. A valve-chamber 10 extends transversely to the axes of the said ports 9, and in this valve-chamber a valve 11 operates, this being in the form of a piston having a port 12 extending through it transversely and adapted to connect the ports 9 in the coupling or valve-casing. This piston-valve is pivotally connected with a piston-rod 13, extending forwardly and connected to a lever 14, pivoted to a suitable bracket on the floor of the engine-house, the said lever extending upwardly and with its upper end arranged to be struck by the shoulder 15 of a part of the pipe 3. Normally the lever rests upon the said shoulder, and with the parts in this position the piston-valve is so positioned that its port is in line with the ports 9 9 and the fuel is free to pass through the valve-casing to the burner, and thus heat the water in the coil 4, which being connected through the pipes 3 with the boiler a circulation will be set up and the water of the boiler will be heated.

In answering an alarm as soon as the engine starts to move from the engine-house the slip-joints at 6 will be operated, disconnecting the parts of the pipes 3 which are fixed to the engine from the portions of the said pipes which are connected with the coil 4, and the check-valves will then operate and automatically close to retain the water in the boiler. At the same time the lever 14 will be operated and the piston-valve 11 will be drawn outwardly from its casing so that port 12 will come opposite a solid part of the casing, and a solid portion of the piston-valve will now extend across the ports 9 9, and thus cut off the fuel from the burner, and the parts will remain in this position until the engine is returned to the engine-house and proper connections are made by means of the slip-joints, when the parts may be readjusted and the burner lighted.

The burner may be of any suitable type, such as a Bunsen burner.

It will be noticed that the heating apparatus is entirely independent of the engine, and the only parts that remain on the engine are the portions of the circulating-pipes 3 connected therewith. The whole device is above

the level of the floor, where it is readily accessible. The piston-valve, it will be noted, operates horizontally, and a direct connection extends therefrom to the lever.

5 I claim as my invention—

In combination with a steam fire-engine, a heating device including a burner circulating-pipes having slip-joint connections, a valve consisting of a piston operating horizontally

10 in a casing and controlling the fuel-supply to the burner, a connection extending horizon-

tally from the said valve, a lever pivotally supported and extending upwardly to be engaged by a part carried by the engine, the said lever being joined to the said horizontal 15 connection, substantially as described.

In testimony whereof I affix my signature in presence of two witnesses.

WILLIAM B. WATERS.
